UNITED STATES PATENT OFFICE.

GEORGE M. WALKUP, OF MINNEAPOLIS, MINNESOTA.

WINDOW STRUCTURE.

Application filed May 24, 1926. Serial No. 111,286.

This invention relates to improvements in window structures, generally, and particularly to such a structure having a sash-carrying frame demountably supported therein, whereby the usual sash may readily be removed from the structure to facilitate cleaning and repairs.

An object of the invention is to provide a window structure comprising a stationary frame, adapted to be mounted in a wall opening, and said frame having an inwardly facing seat provided adjacent the outer portion thereof adapted to demountably receive a storm sash or screen, mounted therein from the interior of the building.

A further object of the invention is to provide such a structure comprising a stationary frame having casings secured to the exteriorly disposed edges thereof and overhanging such edges to provide a seat for a storm sash, and a sash-carrying frame demountably supported in said stationary frame and adapted to engage the storm sash to secure it in its seat in the stationary frame.

A further object is to provide such a structure having a sash-carrying frame demountably supported therein, such frame being provided with a sash-balancing mechanism having connections with the sash, and the sash-carrying frame, including the sash and the sash-balancing mechanism, being removable as a unit from the structure.

A further object is to provide a stationary window frame adapted to demountably receive a sash-carrying frame comprising side grooved jambs and a head jamb secured together as a frame, and spring-actuated sash-balancing drums mounted upon the head jamb and having flexible connections with the sash slidably mounted in the side jambs, and means being provided for locking the sash-balancing drums against movement when the sash are removed from the sash-carrying frame.

A further object is to provide a window structure comprising in combination, a stationary frame having a seat in the outer portion thereof adapted to demountably receive a storm sash, and a sash-carrying frame removably mounted in said stationary frame, and the lower inner portions of the sash-carrying frame being hinged to the major portion thereof whereby the sash may readily be removed from the sash-carrying frame without the necessity of removing

the sash-carrying frame from the stationary frame.

A further object is to provide such a window structure of simple and inexpensive construction, which may be assembled as a unit and mounted in the usual wall opening as an ordinary window frame, thereby providing such a structure well adapted for use in the building art.

Other objects of the invention will appear from the following description and the accompanying drawings, and will be pointed out in the annexed claims.

In the drawings there has been disclosed a structure designed to carry out the various objects of the invention, but it is to be understood that the invention is not confined to the exact features shown, as various changes may be made within the scope of the claims which follow.

In the accompanying drawings:

Figure 1 is a vertical, sectional view of the improved window structure showing it mounted in a wall opening;

Figure 2 is an inside view of Figure 1;

Figure 3 is a view similar to Figure 1, showing the lower portions of the sash-carrying frame swung outwardly to permit the removal of the sash;

Figure 4 is a view similar to Figure 3 with the sash removed from the sash-carrying frame;

Figure 5 is a sectional view of the sash-carrying frame removed from the stationary frame;

Figure 6 is a sectional view of the stationary frame with the sash-carrying frame removed therefrom, showing the method of mounting the storm sash therein;

Figure 7 is a sectional plan view on the line 7—7 of Figure 1;

Figure 8 is a top view of the structure, showing the sash-balancing mechanism mounted thereon;

Figure 9 is a detailed sectional view on the line 9—9 of Figure 8, showing the connections between the sash and the sash-balancing mechanism; and

Figures 10 and 11 are detailed sectional views of the lines 10—10 and 11—11 respectively, of Figure 8, showing the means provided for locking the sash-balancing mechanism against movement when the sash-carrying frame is removed from the stationary frame.

The novel window structure featured in

this invention includes a stationary frame comprising the side jambs 12, sill 13, and the upper cross member 14, suitably secured to the jambs 12, to provide a rectangular frame adapted to be mounted in the usual wall opening 20, as shown in Figure 7. Casings 15 are secured to the outer edges of the side jambs 12, and are adapted to overhang the inner faces thereof, as particularly shown in Figure 7, to provide a seat 16 adapted to demountably receive a storm sash or screen 17, mounted therein from the interior of the building, as shown in dotted lines in Figure 6. A casing board 18 is secured to the upper cross member 14 of the stationary frame, and likewise overhangs the lower face thereof to provide a seat at the upper portion of the frame adapted to receive the storm sash, as shown in the various figures 20 of the drawings.

A feature of this invention resides in the means provided for supporting the usual sash in the stationary frame. Such means consists of a sash-carrying frame demountably supported within the stationary frame. This sash-carrying frame comprises grooved side jambs 19, having their upper ends secured together by means of a similarly grooved head jamb 21. The usual upper and lower sash 22 and 23 are slidably mounted in the grooved or rabbeted jambs 19, as particularly shown in Figures 1, 3 and 7. The lower ends of the grooved side jambs 19 are preferably inclined and adapted to be seated upon correspondingly inclined blocks 24, forming in effect, continuations of the jambs 19, when mounted in the stationary frame. The blocks 24 may be suitably secured to the main jambs 12 of the stationary frame or to the sill 13.

The lower, inner portions 25 of the grooved jambs 19 are pivotally connected to the jambs by means of hinges 26, shown particularly in Figures 3, 4 and 5. These lower hinged sections 25 are provided with grooves 27, adapted to be aligned with the grooves 28 in the jambs 19, when the hinged sections 25 are in normal position, as shown in Figures 1 and 4. By thus pivotally connecting the sections 25 to the jambs 19, the sash 23 may readily and quickly be removed from the sash frame by swinging the sections 25 inwardly to the positions shown in full and dotted lines in Figure 3, after which the sash may be removed from the sash-carrying frame. A suitable fastening means, such as screws 29 and 31, are provided to secure the sash-carrying frame, including the hinged sections 25, to the stationary frame. (See Figures 1 and 4.)

Means are provided at the upper portion of the sash-carrying frame for counter-balancing the weight of the sash. Such means preferably consist of suitable flanged drums 32 and 33, rotatively mounted upon the head

jamb 21, and having flexible connections 34 and 35 connecting them, respectively, with the outer sash 22 and inner sash 23, by such means as hooks 36. Each pair of drums 32 and 33 are connected together by means of cross members 37, each having a torsion spring 38 mounted therein, as shown in Figure 9. Each torsion spring 38 has one end secured to a member 37 and its other end secured to one of the brackets 39 supporting the drums 32 and 33. These springs are constantly under tension and tend to rotate the drums 32 and 33 in a direction to lift the sash 22 and 23. The tension of the springs 38 is sufficient to substantially counterbalance the weight of the sash.

Means are provided for locking the drums 32 and 33 against movement when the sash are to be removed from the sash-carrying frame for such purposes as cleaning or repairs. Such means preferably consist of threaded stems 41 and 42, rotatively mounted in brackets 43, secured to the upper portion of the head jamb 21. Angle brackets 44 and 45 are received in threaded engagement, respectively, with the threaded stems 41 and 42, and are adapted to be moved into and out of engagement with the cross members 37 by rotation of the stems 41 and 42. (See Figures 10 and 11.) The portions of the angle brackets 44 and 45 engaging the members 37 are preferably corrugated or roughened, to provide a gripping surface adapted to arrest the movement of the members 37, when the brackets are moved into engagement therewith, and the sash are removed from the flexible connections 34 and 35. Each threaded stem is terminally squared to receive a suitable key member (not shown) inserted through openings 46, provided in a finishing plate 47, secured to the inner face of the inside top casing 48, as shown particularly in Figure 2. Inner side casings 49 may also be secured to the inner edges of the main jambs 12 to provide a finished appearance of the frame within the building, as is customary in window structures of ordinary construction.

The construction of this novel window structure is such that it may be mounted in wall openings of ordinary size, such as are commonly provided for ordinary window frames. The stationary frame, including the outer casings 15 and 18 and also the demountable sash-carrying frame comprising the grooved jambs 19 and 21, may be assembled as a unit and mounted in the wall opening as an ordinary window frame. By removing the sash-carrying frame from the stationary frame, the sash may readily be mounted therein and connected to the sash-balancing mechanism at the upper portion thereof, after which the sash-carrying frame, with the sash mounted therein, may be mounted as a unit in the stationary frame

and secured therein by means of the screws 29 and 31. The grooved jamb 21 of the sash-carrying frame is preferably relatively thicker than the upright jambs 19, in order 5 to provide a shoulder 51 adapted to abut against the adjacent edge of the cross member 14 of the stationary frame, to provide a limit stop for the inward movement of the sash-carrying frame. By hinging the lower, 10 inner portions 25 of the side jambs 19 the lower, inner sash may readily be removed from the sash-carrying frame, as shown in Figure 3 and as hereinbefore described.

The upper sash may also be removed from 15 the sash-carrying frame by disconnecting it from the sash-balancing mechanism and lowering it to the bottom of the frame, after which, when the hinged sections 25 are 20 swung upwardly to the position shown in the dotted line in Figure 3, the outer sash may be tilted outwardly, as indicated by dotted lines in the same figure after which it may be readily lifted clear of the sash-carrying frame for cleansing or repairs. 25 The lower glazings or panes 52 of the storm sash 17 may be mounted in a frame 53 hinged to the frame of the storm sash, whereby they may be swung outwardly to an open position to admit fresh air into the 30 building. The storm sash may readily be removed from its seat after the sash-carrying frame has been removed from the stationary frame, as clearly shown in Figure 6. When the storm sash is mounted in the 35 stationary frame and the sash-carrying frame also is mounted therein, as shown in Figure 4, the latter will engage the storm sash and securely hold it in its seat, thereby preventing cold air or moisture from entering 40 the building between the storm sash and its supporting means.

It will also be noted that the storm sash may be mounted in the stationary frame and removed from the interior of the building, 45 thereby eliminating the usual disadvantages encountered when hanging or mounting storm windows and screens from the exterior of the building, as is customary with present window structures.

50 I claim as my invention:

1. The combination with a window structure comprising a frame adapted to be secured in a wall opening and adapted to have a sash mounted therein, of an inwardly 55 facing seat in said frame adapted to demountably receive a storm sash from the interior of said frame.

2. The combination with a window structure comprising a frame adapted to be secured in a wall opening, of an inwardly 60 facing seat in said frame adapted to receive

a storm sash, and a sash-carrying frame demountable in said stationary frame and adapted to secure said storm sash therein.

3. A window structure comprising a stationary frame adapted to be secured in a wall opening, a seat in said frame adapted to receive a storm sash, and a sash-carrying frame demountably supported in said stationary frame and adapted to engage said 70 storm sash to secure it in said seat.

4. A window structure comprising a stationary frame, casings secured to the exteriorly disposed edges thereof, said casings inwardly overhanging said frame to provide 75 a seat for a storm sash adapted to be mounted therein from the interior of said frame.

5. A window structure comprising in combination, a stationary frame having casings secured to the exteriorly disposed edges 80 thereof in overhanging relation thereto to provide a seat for the storm sash, a sash-carrying frame demountably supported in said stationary frame and co-operating therewith to secure said sash in said seat, 85 and means for securing said sash-carrying frame in said stationary frame.

6. A window structure comprising in combination a stationary frame adapted to be mounted in a wall opening, a sash-carrying 90 frame demountably supported in said stationary frame, and said sash-carrying frame comprising grooved side jambs secured together at their upper ends only.

7. A window structure comprising a stationary frame, an inwardly facing seat in said frame adapted to demountably receive a storm sash, a sash-carrying frame also demountably received in said stationary frame, said sash-carrying frame comprising upright 100 grooved jambs having a grooved head jamb secured thereto, a sash-balancing mechanism carried by said head jamb, and said sash-carrying frame, including the sash and sash-balancing mechanism, being adapted to be 105 removed as a unit from said stationary frame to permit removal of the storm sash from the interior of a building.

8. A window structure comprising a stationary frame having an inwardly facing 110 seat for a storm sash, a sash-carrying frame demountably supported in said stationary frame and adapted to secure a storm sash in said seat, and a section of said sash-carrying frame being hinged to permit the removal of the sash without removing said sash-carrying frame from said stationary frame.

In witness whereof, I have hereunto set my hand this 21st day of May 1926.

GEORGE M. WALKUP.
